UNITED STATES PATENT OFFICE.

BENJAMIN WISE, OF NEW YORK, N. Y.

DESIGN FOR A TELEPHONE-RECEIVER HOLDER.

59,801.

Specification for Design.

Patented Nov. 22, 1921.

Application filed April 9, 1921. Serial No. 460,083. Term of patent 7 years.

To all whom it may concern:

Be it known that I, BENJAMIN WISE, a citizen of the United States of America, residing at New York, in the county and State of New York, have invented a new, original, and ornamental Design for a Telephone-Receiver Holder, of which the following is a specification, reference being had to the accompanying drawing, forming part thereof.

The figure is a perspective view of a telephone receiver holder showing my new design, its relation to the telephone being indicated in dot and dash lines.

I claim:

The original design for a telephone receiver holder, as shown.

BENJAMIN WISE.
